UNITED STATES PATENT OFFICE.

PERCY GORDON ECKERSLEY DANIEL, OF CLEVEDON, AND CHARLES ASHTON HENRY BULLOCK, OF LONDON, ENGLAND.

MACHINE FOR SUPPLYING AND AFFIXING STAMPS.

1,029,671.

Specification of Letters Patent. Patented June 18, 1912.

Application filed June 23, 1909. Serial No. 503,940.

To all whom it may concern:

Be it known that we, PERCY GORDON ECKERSLEY DANIEL and CHARLES ASHTON HENRY BULLOCK, subjects of the King of Great Britain, residing the first-named at Clevedon, in the county of Somerset, England, and the second-named at London, in the county of London, England, have invented a new and useful Improvement in Machines for Supplying and Affixing Stamps, of which the following is a specification.

This invention relates to improvements in machines for supplying and affixing adhesive stamps and vouchers.

15 This invention relates to improvements in machines for supplying and affixing stamps, vouchers and the like, and consists of certain improvements and modifications in the construction and arrangement of the operating parts of the machine, which result in the provision of a machine of more simple and inexpensive construction and of greater efficiency and reliability in use than those hitherto proposed.

25 An important feature of the original invention consists in the means for feeding the stamp strip and one object of the present invention is the provision of a feeding device involving the same principles, but of such a construction that immediately the stamp has been fed forward the desired distance, the feed carriage flies back again to its position of rest and remains in that position until the operating handle has also been allowed to return to the normal position and then again operated. By this means the machine can be operated more rapidly than heretofore and with less liability to fail. This will be readily understood when it is remembered that in the present construction the feed carriage, at once returning to its position of rest before the plunger has reached its lowest position, has ample time to insure the whole of its working parts returning to their normal positions ready for the next operation. Moreover the present arrangement and construction of feeding device enable the last stamp of the strip to be delivered from the machine since the feeding arm engages the perforations between the first and second instead of the second and third stamp upon the strip as in the former construction, and this also insures a better feed for it will be readily understood that if the stamp is di-

rectly pushed forward there is less liability to cockle than if—as in the previous construction—the second stamp of the strip were really being moved forward to push the stamp in front of it into position for use.

A further feature of our invention consists in the provision of duplicate water tanks—or a common water tank having duplicate discharge pipes—of improved construction and designed to be so operated that the water is discharged in the proper direction. Moreover the casing instead of being cut away entirely is bored or provided with suitable openings for the water to pass through. By this means the stamp is guided the whole way down and there is less liability of its becoming displaced. And in order that this our invention may be more readily understood and carried into practical effect, reference is hereby made to the accompanying sheets of illustrative drawings wherein—

Figure 1 is a vertical section of a machine constructed in accordance with our invention. Fig. 2 is an elevational view thereof. Fig. 3 is an under-plan view thereof. Fig. 4 is a sectional view illustrating the construction of the water tanks. Figs. 5 and 6 are plan and elevational views respectively of a modified form of water tank and its operating connections, while Fig. 7 is a view showing a modified construction of stamp strip guide.

Referring to these drawings wherein like letters of reference indicate corresponding parts wherever occurring A designates a casing within which a plunger B slides. The plunger B carries a V-shaped knife B¹ which operates to cut off each stamp from the strip as will hereafter appear. A plunger rod B² passes upward through a guide or orifice A¹ in the top of the casing and the upper extremity of this rod B² is provided with an operating handle or knob B³. Springs B⁴ and B⁵ operate to maintain the plunger in its normal or raised position. The plunger proper B preferably consists of a rubber or other yielding buffer, and the lower surface of this buffer is somewhat concave while the openings B⁶ are provided to give the said buffer increased flexibility.

Proceeding from a slot in the casing A we provide the stamp strip guide C and this guide has a feed carriage D adapted to slide

freely upon it, its forward movement being limited by a suitable stop D^5 conveniently arranged near the lower end of a rocking lever E . The feed carriage D carries a pivoted and spring controlled feeding arm or member D^1 and the forward end of this feeding arm or member D^1 has depending bevel teeth D^2 , which in operation engage the perforations of the stamp strip. Pivoted at A^2 to the top of the casing A we provide a flexible spring controlled arm or rocking lever E and the lower end of this flexible arm or lever E is provided with a bifurcated or slotted block E^1 which engages the pin D^3 upon which the spring controlled feeding arm D^1 is pivoted. This arm E is normally held in its outward position shown in Fig. 1 by means of the knife spring E^3 . At a convenient position toward the upper end of the flexible arm or lever E a beveled catch or projection E^2 is pivoted and this catch E^2 is normally held in its operative position by means of a suitable spring such as E^4 . The plunger rod B^2 carries a horizontally projecting member B^7 which passes through a slot in the casing A , and carries at its extremity a roller B^8 , which roller B^8 coöperates with the catch E^2 in a manner which will hereafter be made clear. Upon the side of the flexible arm E opposite that upon which the pivoted catch E^2 is carried, a fixed wedge or safety catch E^5 is attached and a roller B^{12} carried by the plunger rod B^2 operates against this catch so as to provide against any liability of the feed carriage D remaining too long in its forward position.

It will be clear that immediately the roller B^{12} contacts with the fixed wedge or safety catch E^5 the tendency of the feed carriage D is to return to its normal position both under the influence of its spring, and also by the operation of the roller B^{12} against this catch. It will of course be understood that this catch E^5 is so situated as to come into operation immediately the roller B^8 has passed the pivoted catch E^2 . As a matter of fact, this safety catch does not always come into operation but is provided merely as a safety device for fear any outside agency should operate to retard the return movement of the carriage D .

Upon a suitably disposed bracket F carried by the casing A a removable stamp spool F^1 is mounted and the stamp strip F^2 is fed from this spool between the guide rollers F^3 and F^4 into the stamp strip guide C . The guide roller F^4 is preferably carried by the pivoted member F^5 and is maintained in contact with the roller F^3 by means of the spring F^6 .

Pivoted upon the sides of the casing A arms G are arranged and the lower ends of these arms are connected to and carry the water tanks G^1 . The arms G upon one side

carry pivoted catches G^2 and the two arms are caused to tend to come together by means of the spring G^3 or by any other suitable means. Associated with the plunger rod B^2 a wedge or cam block G^9 is provided, which wedge or cam block is adapted to co-operate with the pivoted catches G^2 in a manner which will hereafter appear. The water tanks G^1 are constructed as shown in Fig. 4, baffle plates G^4 extending almost entirely across the bottom of the tank, while funnel shaped pipes G^5 extend from the top of the tanks to the bottom, small orifices G^6 being provided in the bottom of the pipes G^5 so that the water within the tanks has access to the pipes G^5 . The tops of the tanks are provided with pin holes G^8 centrally of the funnel shaped pipes G^5 and jets or nozzles G^7 are provided through which the water for effecting the damping of the envelope or the like is ejected. The baffles G^4 are provided so that a regular weight and volume of water shall at each operation be discharged at the jets or nozzles G^7 while the funnel shaped pipes G^5 are provided, in order to prevent leakage at the nozzles when, owing to handling or other causes, expansion consequent upon a rise in temperature takes place within the tanks. It has been found in practice that if hermetically sealed tanks are employed, the mere handling of them is sufficient to cause such an expansion of the contents as will cause a slight leakage at the jets. In the present construction the expansion would cause the volume of liquid within the tanks to rise in the pipes G^5 instead of leaking through the jets G^7 . This is a point of some practical importance, since it renders the machine absolutely cleanly in use.

Suitably situated we provide the counting device H of known construction. This counting device is operated by a pivoted lever H^1 which coöperates with a catch B^{10} carried by the plunger rod B^2 . The lever H^1 is controlled by the light leaf spring H^2 so that the mechanism of the counting device returns to its normal position after each operation ready for the next operation.

In operation the stamp strip is fed from the spool F^1 through the guide C until the perforations between the first and second stamp of the strip engage upon the tooth C^1 carried by the pivoted lever C^2 , and in order to facilitate this initial adjustment both the lever C^2 and the feeding arm D^1 are provided with finger pieces C^3 and D^4 which can be pressed together so as to lift the tooth C^1 and the teeth D^2 out of the way for the moment. Assuming that the stamp strip is in position with the tooth C^1 engaged in the perforations between the first and second stamp of the strip, the machine is now ready for operation and it will be noticed that the stamp strip cannot have any retro-

grade movement accidentally imparted to it, owing to the tooth C¹. The device as a whole is now lifted on to the envelop or the like upon which it is desired to affix a stamp. The plunger is now depressed and the roller B⁸ carried by the member B⁷ descends and engages the catch E² in cam fashion against it, causing the flexible arm E to move about its pivot A² and thus the feed carriage D is moved forward. The normal position of the feed carriage is such that the teeth D² are situated somewhere between the perforations separating the first and second, and the second and third stamps of the strip. That is to say, such teeth are resting somewhere on the second stamp of the strip. As the feed carriage D slides forward, the teeth D² must therefore fall firmly into the perforations between the first and second stamp immediately such teeth reach a position coincident with such perforations, and it follows that the further movement of the feed carriage or slide D will cause the first stamp to be carried forward and this stamp is in fact carried forward until the adjustable stop D⁴ contacts with the casing A and when in this position, the perforations between the first and second stamps of the strip lie exactly under the knife B¹. This method of feeding is of great importance because it avoids the great difficulty which has hitherto been experienced in machines of this class, where the feed is designed to move forward a definite distance. It has been found in practice impossible to feed forward a definite distance without the possibility of slight error which, accumulating at every operation, soon renders the machine so much out of adjustment that the stamps eventually get cut off in the middle. It will be noticed that in our machine although there may be error in the actual distance of the feed, the error does not matter since whatever happens the feed slide moves forward to a definite point after which any further tendency to feed is taken up by the resilient arm (in this case E). Immediately the roller B⁸ has passed the catch E², the arm E flies back under the influence of its spring E³, and in order to limit the rearward movement of the feed slide or carriage D a stop C⁴ is fixed upon the guide C. This stop need not be adjustable since it is immaterial how far the slide moves back so long as the teeth D² take up a position somewhere upon the second stamp of the strip. As previously stated any tendency of the feed carriage to remain in the forward position is obviated by the safety catch E⁵ as before described. Simultaneously with the movement of the feed slide or carriage D in the manner before described, the wedge or cam block G⁹ operates upon the pivoted catches G² and in order to render the opera-

tion free from concussion these catches are provided with springs G⁴ which absorb any shock consequent upon the first contact of the cam block G⁹ with them. The cam block G⁹ operating against the catches G² causes the levers G to move about their pivots against the influence of the spring G³ and the tanks G¹ are thus carried out. Immediately however the cam block G⁹ has passed the catches G², the levers G come together sharply under the influence of the said spring G³ and the shock thus imparted causes the ejection or discharge of minute particles of water through the nozzles G⁷, and the moisture thus provided is directed through the perforations A³ in the casing A upon the envelop or the like immediately beneath. This operation is arranged to take place just before the plunger B finally descends so that when this damping operation has been effected and the stamp has been fed forward to its correct position, the plunger still continues to descend and the knife B¹ cuts off the stamp and the plunger B presses it on to the already damped envelop. In its downward movement the plunger rod B², by means of the catch B¹⁰ engaging the pivoted lever H¹ also operates the counting device H so that the fact that a stamp has been withdrawn from the machine is automatically recorded. The plunger knob is now released and the plunger and its rod return to their normal positions ready for the next operation.

We have described our machine as having duplicate water tanks simultaneously operated to discharge liquid beneath the stamp, but the same effect may be produced by providing one common tank as shown in Figs. 5 and 6. In this case the tank I is in the main constructed on the lines of those previously described but such tank is provided with side pipes I¹ having jets or nozzles I². The tank is arranged to slide horizontally against the influence of the centrally situated spring I³ when the plunger rod B² descends, a catch such as B¹¹ upon the plunger rod operating cam fashion against a pivoted catch I⁴ associated with the tank through the pivoted rod I⁵, causing such tank to be operated in a manner which will be readily understood, to cause jets of moisture to be thrown by concussion from the jets or nozzles I². Although in this case the bodily movement of the tank I would be at right angles to the direction in which the moisture is to be sprayed it has been found by experiment that the water is discharged from the nozzles in the desired direction and falls upon the envelop beneath the stamps to be affixed.

In order to provide against any splashes of water which might inadvertently drop on the base outside the casing A remaining thereon, we provide said base with an ab-

sorbent pad J so that even if some drops of water do fall outside, they become immediately absorbed, thus insuring the cleanliness of the apparatus when in use.

5 In Fig. 7 we have shown the guide C curved and although this may not be quite so advantageous from the point of view of manufacture it has some advantages. Not only does it permit the stamp spool to be 10 so situated that the guide rollers F³ and F⁴ may be dispensed with, but it offers a slight resistance to the passage of the stamp strip and thus prevents any liability of the last stamp of the strip being fed forward too 15 freely.

It will thus be seen that a machine constructed in accordance with the present invention, at each operation automatically 20 performs the functions of automatically feeding the stamp forward, cutting off a stamp from the strip, damping the envelop or the like, and affixing said stamp thereto.

What we claim as our invention and desire to secure by Letters Patent, is:—

25 1. In machines for supplying and affixing stamps, the combination of a casing, a plunger sliding within the casing, a stamp strip guide proceeding from the casing, a stamp strip feeding carriage, sliding in the stamp strip guide, a spring controlled flexible feed arm pivoted at its upper end to the casing and engaging the feed slide at its lower end, a pivoted spring controlled catch carried by the feed arm, an obstruction carried by the plunger and coöperating with 30 the pivoted catch to move the feed slide forward, an adaptable stop to limit the forward travel of the feed carriage, a damping device adapted to spray moisture on to the 35 surface to which the stamp is to be affixed, a cutting device and an affixing device, substantially as specified.

40 2. In machines for supplying and affixing stamps, the combination of a casing, a plunger sliding within the casing, a stamp strip guide proceeding from the casing, a stamp strip feeding carriage, sliding in the stamp strip guide, a spring controlled flexible feed arm pivoted at its upper end to the 45 casing and engaging the feed slide at its lower end, a pivoted spring controlled catch carried by the feed arm, an obstruction carried by the plunger and coöperating with the pivoted catch to move the feed slide forward, a safety catch carried upon the flexible feed arm, an obstruction carried by the plunger and coöperating with the safety 50 catch to insure the rapid return of the feed carriage, an adjustable stop to limit the forward travel of the feed carriage, a damping device adapted to spray moisture on to the 55 surface to which the stamp is to be affixed, a cutting device and an affixing device, substantially as specified.

60 3. In machines for supplying and affixing

stamps, the combination of a casing, a plunger sliding within the casing, a stamp strip guide proceeding from the casing, a stamp strip feeding carriage, sliding in the stamp strip guide, a spring controlled flexible feed arm pivoted at its upper end to the casing and engaging the feed slide at its lower end, a pivoted spring controlled catch carried by the feed arm, an obstruction carried by the plunger and coöperating with the pivoted catch to move the feed slide forward, an adaptable stop to limit the forward travel of the feed carriage, duplicate damping devices, means for operating said damping devices to spray moisture in diametrically opposed directions on to the surface to which the stamp is to be affixed, a cutting device and an affixing device, substantially as specified.

4. In machines for supplying and affixing stamps, the combination of a casing, a plunger sliding within the casing, a stamp strip guide proceeding from the casing, a stamp strip feeding carriage, sliding in the stamp strip guide, a spring controlled flexible feed arm pivoted at its upper end to the casing and engaging the feed slide at its lower end, a pivoted spring controlled catch carried by the feed arm, an obstruction carried by the plunger and coöperating with the pivoted catch to move the feed slide forward, a safety catch carried upon the flexible feed arm, an obstruction carried by the plunger and coöperating with the safety catch to insure the rapid return of the feed carriage, an adjustable stop to limit the forward travel of the feed carriage, duplicate damping devices, means for operating said damping devices to spray moisture in diametrically opposed directions on to the surface to which the stamp is to be affixed, substantially as specified.

5. In machines for supplying and affixing stamps, the combination of a casing, a plunger sliding within the casing, a stamp strip guide proceeding from the casing, a stamp strip feeding carriage, sliding in the stamp strip guide, a spring controlled flexible feed arm pivoted at its upper end to the casing and engaging the feed slide at its lower end, a pivoted spring controlled catch carried by the feed arm, an obstruction carried by the plunger and coöperating with the pivoted catch to move the feed slide forward, an adaptable stop to limit the forward travel of the feed carriage, a spring controlled pawl device for preventing retrograde movement of the stamp strip after it has been fed forward, a damping device adapted to spray moisture on to the surface to which the stamp is to be affixed, a cutting device and an affixing device, substantially as specified.

6. In machines for supplying and affixing stamps, the combination of a casing, a

plunger sliding within the casing, a stamp strip feeding device operated by the plunger, to feed the stamp strip forward, duplicate water carrying tanks, diametrically opposed discharge nozzles proceeding from the tanks, levers pivoted to the casing at their upper ends and carrying the water tanks at their lower ends, means carried by the plunger rod for causing the levers to move about their pivots and carry the water tanks out as the plunger is depressed, a spring for rapidly restoring said levers to their normal positions so as to cause moisture to be discharged by concussion from the nozzles aforesaid in diametrically opposite directions on to the surface to be moistened, a cutting device and an affixing device, substantially as specified.

7. In machines for supplying and affixing stamps, the combination of a casing, a plunger sliding within the casing, a stamp strip feeding device operated by the plunger

to feed the stamp strip forward, duplicate water carrying tanks having nozzles diametrically opposed, rocking levers conveying said tanks, catches, pivoted to the rocking levers, an obstruction carried by the plunger rod coöperating with the pivoted catches to rock the levers in opposite directions, a spring operating to rapidly draw the levers together again when the obstruction on the plunger has passed the pivoted catches, whereby moisture is discharged from the diametrically opposed nozzles on to the surface to be moistened, a cutting device and an affixing device, substantially as specified.

In witness whereof we have hereunto set our hands in the presence of two witnesses.
